United States Patent Office.

GEORGE SUMNER ALBEE, OF HOPKINTON, MASSACHUSETTS.

Design No. 4,623, dated February 7, 1871.

DESIGN FOR A HEATER FOR MILK, &c.

The Schedule referred to in these Letters Patent and making part of the same.

I, GEORGE SUMNER ALBEE, of Hopkinton, in the county of Middlesex and State of Massachusetts, have invented a new and original Design for a "Heater," for heating milk, water, tea, &c., by means of burning alcohol, of which the following is a specification.

On the drawing is shown a perspective view of my design for a heater.

My invention refers to a new and original shape and configuration for a heater of the kind generally known as "Ætna burners."

a on the drawing is the receptacle for the liquid;
b is the spout;
c is the cup for containing alcohol;
d is the base; and
e is the handle.

I claim as my invention—

The design for a heater, as herein shown.

GEORGE SUMNER ALBEE. [L. S.]
